TRAFFIC SIGNAL

Application filed March 21, 1927. Serial No. 177,125.

This invention relates to devices to be used for giving proper suspension to traffic signal lanterns when such lanterns are to be hung over highways. When, as is usually the case, the signal lights are carried in a series of superposed lantern elements, the lantern hung as it is from the top, becomes subject to wind pressure so that the lantern has a swinging motion, seriously impairing its use-
fulness and durability. The rays of light issuing from such signal lanterns are intended to be concentrated through suitable lenses into beams of light that may be directed along and preferably down upon a roadway. Such directing of the light beams necessarily calls for rigidity of lantern both as regards swinging and turning which ordinary suspensions have not given.

The present invention comprises means for suspending such lanterns combined with means for bracing the lantern so that the beams of light projecting therefrom will bear a fixed relation to the roadway.

The invention comprises further details of construction hereinbelow described and claimed.

An embodiment of the invention is illustrated in the accompanying drawings, in which

Figure 1 is a perspective view of a signal lantern suspended according to my invention.

Figure 2 is a side elevation of a modified form of suspension.

Figure 3 is an end elevation of a suspension embodying further features.

Figure 4 is a plan view in partial section, on line 4-4 of Figure 2.

Referring to the drawings, a signal lantern is shown at 1 as composed of four super-posed lantern elements, each element having concentrating lenses 2 on each of its four sides, the particular lantern shown being adapted to be suspended over a junction of two streets so as to throw beams of light along the streets to operate as traffic signals,

it being understood that the various elements have lenses of different colors to give the proper significance to control the traffic. In the instance shown, where there are four superposed lantern elements, one element will give the red and green rays for traffic in one direction, another element giving at the same time green and red rays. A third element will be used for amber lights on all sides to indicate that interim between the two periods of traffic. The fourth element will have all red lights to indicate entire stoppage of traffic, as for example when traffic must be held still for fire service. The lantern is suspended from cross wires 3 and 4 which may be either arranged in a horizontal plane, as shown in Figure 1, or in a vertical plane as shown in Figures 2 and 3. In either case, they are bridged by a cross member 5 which is clamped at both ends to the wires. The suspension wires and the cross member thus form a frame from which the lantern may not only be suspended but also braced. In Figure 1, the suspension is shown by the lantern being fastened at its upper end as shown at 6 in the mid length of the cross member. Braces or guys 7 attached securely to the cross wires at 8 have their lower ends secured to the base of the lantern or, as is shown in Figure 1, to the ends of a lower brace 9 that is clamped to the lower end of the lantern. In Figure 2, a similar construction is used for suspension wires arranged in a vertical plane. In this case, however, the bridge piece has lateral extensions 5' from which suitable guy wires or rods 10 lead to the lower brace 9, which may be in the form shown in Figure 4, with four arms. As shown in Figure 2, wires 11 bracing the lantern from vibration in line with the suspension wires may be secured to the cross wires at their upper ends and to the brace 9 or the base of the lantern at their lower ends. In Figure 3 is shown a modification in which the lantern is hung in a position considerably below the cross suspension

wires 3 and 4, there being introduced intermediate guy wires 12 to support a lower framework in a rigid manner, the lower framework itself being composed of cross members 13. The lantern may be braced by wires or bars 18 extending from the suspension members to a point sufficiently below the top of the lantern to give the required stability. The object of this construction is to enable the lantern to be suspended, for example, adjacent to trolley or other wires 14 and yet be held sufficiently rigid to not only preserve the alignment and orientation of the beams of light, but also to prevent the lantern from swinging against the trolley lines, which has heretofore been known to cause considerable damage. To further safeguard against damage from short circuits in case trolley wires should come in contact with the lantern, the lantern and its frame may be insulated from the cross wires, as shown at 15, by insulating material interposed between the suspension wires and the cross beam or the insulation may be interposed between the cross wires and their end supports. The end supports are shown in Figure 1 as constituted by a cross brace 16 properly clamped on a post 17. With such an end support as 16 rigidly secured to a post, a spreader is formed for securing the cross wires in a horizontal plane so that when the bridge piece 5 is added, a horizontal suspension member is formed of the rigid end supports, the middle bridge and the suspension wires that will give a stable mounting from which a lantern may be properly suspended in a vertical position and held therein by suitable guy wires from the lantern to the supporting member. Of course, the post itself may be used as a spreader and the cross wires placed vertically as shown in Figures 2 and 3 but in this case it becomes necessary to have the bridge member 5 provided with horizontal extension 5' so that in effect the same result is accomplished as in Figure 1, namely a cross member between two poles of some lateral stability with a bridge member clamped to the cross member and having horizontal spread. In both cases the guy wires 7, 11, 12 and 18 reach from the lantern to the cross member and hold the lantern in its vertical position solely by virtue of the stability of the cross member as a framework. It is important to have the lantern pivotally attached as shown at 6 so that it may be allowed to assume a vertical position by gravity before the guy wires are attached.

I claim:-

1. The combination comprising two suspension wires having their ends rigidly held by end spreaders a fixed distance apart, a rigid bridging member between the wires forming with the wires and the rigid end spreaders a stable supporting means, said bridging member having a horizontal exten-

sion, a lantern vertically suspended below the said rigid member on a pivot, and guy wires from the lantern to the supporting means for holding the lantern in all directions against vibration.

2. A construction according to claim 1 in which the cross wires are vertically disposed and the cross member has vertical portions clamping the wires, and horizontal extension for giving lateral stability to the lantern.
